FRED E. ASELTINE, OF DAYTON, OHIO, ASSIGNOR TO DELCO PRODUCTS CORPORATION,
OF ANDERSON, INDIANA, A CORPORATION OF DELAWARE

CHARGE FORMING DEVICE

Application filed September 7, 1929. Serial No. 391,059.

This invention relates to charge forming devices for internal combustion engines, and more particularly to devices of this character which comprise a plurality of primary carburetors which deliver a primary mixture of fuel and air to a plurality of secondary mixing chambers located adjacent the engine intake ports, and in which the primary mixture is mixed with additional air under certain operating conditions.

A device of this character is disclosed in the copending application of Fred E. Aseltine, Wilford H. Teeter and Carl H. Kindl, Serial No. 288,683, filed June 10, 1928, to which reference may be had for a full disclosure of the device shown herein.

It is the main object of the present invention to provide a device of the character above referred to, having improved means for controlling the proportions of the mixture during operation following any opening of the throttle valve, and more particularly, to provide means for preventing too great enrichment of the mixture when the throttle is opened and the engine is already running at relatively high speed.

It is a further more specific object of the invention to provide improved means for retarding the opening movements of the main and auxiliary air valves which is of simple design, comprises few moving parts and is effective to retard the opening of the valves to the same extent, regardless of the position the valves occupy when such opening movement takes place.

In earlier devices of this character means have been provided retarding the opening movement of both the main and auxiliary air valves on any opening movement of the throttle. It is desirable to render such retarding means ineffective when the throttle is open and the engine is running at high speeds because reduction of the opening of the air valve under such operating conditions would cause an enrichment of the mixture which is not desirable at such time. According to the present invention, the retarding means for both the main air valve and the auxiliary air valve becomes ineffective by a single device when the valves are opened

under the operating conditions referred to and both valves are permitted to open relatively freely at this time.

Further objects and advantages of the present invention will be apparent from the following description reference being had to the accompanying drawing wherein a preferred embodiment of one form of the present invention is clearly shown.

In the drawing:

Fig. 1 is a vertical, longitudinal section through a charge forming device constructed in accordance with the present invention and the intake port with which it is associated.

Fig. 2 is a fragmentary, transverse, vertical section on the line 2—2 of Fig. 1.

The device disclosed comprises a main air manifold 10, having three outlet branches, the middle branch 12 being shown herein. Each of these branches communicates with one of the intake ports 14 of a multicylinder engine. The outlet branches are each provided with an attaching flange 16 for securing the manifold to the engine block in the usual manner, and a flange 18 to which the carburetor unit is secured.

The carburetor unit comprises a main housing 20, having an attaching flange 22, adapted to be secured to the flange 18 by screws 24. An air inlet coupling 28 is secured in position to register with an opening in the upper wall of the housing 20, in any suitable way and may be connected with an air cleaner if desired. A casting 30, in which the passages supplying fuel to the nozzles are formed, is secured by screws to the lower wall of housing 20, and a sheet metal fuel bowl 32 is held tight against an annular shoulder 34 on the housing 20 by any suitable means.

Fuel is conducted from a main source of supply to the fuel bowl through a conduit (not shown) and the flow of fuel to the bowl is controlled by a float which is not illustrated but operates in the usual manner to maintain a substantially constant level of fuel therein, as described in said earlier case.

Fuel flows from the bowl 32 to a plurality of primary fuel nozzles 38, one of which is located in each of the primary mixing cham-

bers 40, the construction of which is briefly described hereinafter. The fuel conduit between the fuel bowl and the nozzles comprises the vertical fuel passage 42 communicating at its upper end with the horizontal fuel canal 44, which connects with each of the nozzles 38 through an orifice 46. Fuel is admitted from the fuel bowl to the passage 42 at all engine speeds, through a fixed metering orifice 48 and at high speeds additional fuel is admitted through an orifice 50 controlled by a valve 52, operated in the manner set forth in the above mentioned application. This operating means forms no part of the present invention and need not be described further herein.

Fuel is lifted from the fuel bowl through the above described fuel passages and nozzles 38 to the primary mixing chambers by the suction therein. Opening movements of the throttle cause a reduction in mixing chamber suction which might permit the fuel column to drop sufficiently to cause a temporary fuel starving of the engine unless means are provided to prevent this action. For this purpose a check valve 54 is provided in an enlarged chamber 56 at the junction of the channels 42 and 44, and on reduction of mixing chamber suction, seats on the bottom of the chamber, preventing downward flow of fuel.

Each primary fuel nozzle is provided with a main fuel outlet 58 in the top of the nozzle and a secondary fuel outlet comprising two orifices 60 and 62 in the vertical wall of the nozzle near the bottom of the mixing chamber. At relatively high speeds, the mixing chamber suction is sufficient to lift fuel from the main outlet as well as from orifices 60 and 62. At idling, or low speed operation under load, however, the suction is enough to lift fuel only to some point between the top of the nozzle and the orifices 60 and 62, fuel flowing from these orifices by the action of gravity under such operating conditions. Each nozzle is provided with a restricted fuel metering orifice 63. The primary mixing chamber comprises the enlarged anterior ends of the primary mixture passages 64, which are parallel to each other and close together, as indicated in Fig. 2. When the carburetor is attached to the manifold, these passages register with conduits which convey the primary mixture to the secondary mixing chambers, as fully disclosed in the application above referred to. Restrictions 66 separate the primary mixing chambers from the remainder of the mixture passages to reduce the velocity of flow past the fuel nozzles for a purpose fully set forth in the above mentioned copending application.

A single throttle valve 68, which extends across all the primary mixture passages, controls the flow therethrough and is provided with grooves 70, which register with said

mixture passages. This throttle is operated in a manner hereinafter more fully described. The middle primary mixture passage communicates with a tube 72 fixed in the manifold branch 12. This tube constitutes one of the primary mixture conduits above referred to and conveys the primary mixture to the secondary mixing chamber located in the middle branch of the manifold.

Nearly all of the air entering the carburetor flows through the inlet coupling 28 and is controlled by the main air valve 74, normally held against a seat 76 by a spring 78, received between the valve and a flange 80, projecting from a sleeve 82, slidably mounted on a stationary guide sleeve 84, fixed in the housing 20, and serving also as a guide for the stem 86 to which the air valve is secured. When it is desired to choke the carburetor to facilitate starting of the engine, the flange 80 is adapted to be lifted by means not shown herein, but fully described in the above application, until the upper end of the sleeve 82 engages the air valve to hold it closed. Sufficient air to carry the starting fuel from the nozzles to the intake ports is admitted through an elongated slot 87, formed in a plate 88, secured to the housing 20, as shown in Fig. 1.

The valve 74 admits air to the air chamber 90, from which air flows to the primary mixture passages through an orifice 92 in the bottom of the air chamber and to the secondary mixing chambers through a passage 94, which connects with the inlet of the manifold 10. The flow of air through this passage is controlled by a manually operable throttle 96, secured to a shaft 98, rotatably mounted in the main housing and by a suction operated valve 100, secured to a shaft 102, also rotatably mounted in the main housing.

The operating connections for the two throttle valves constitute no part of the present invention and are not described herein, it being sufficient for the purposes of this disclosure to describe briefly the mode of operation of these valves. The primary throttle is connected to the main air throttle 96 by a lost motion connection, which permits a predetermined movement of the primary throttle independent of the throttle 96, and is capable of adjustment. It is generally adjusted so that the primary throttle is movable without accompanying movement of the air throttle until the former reaches a position corresponding to a vehicular speed of approximately 15-20 miles per hour on the level. On further opening of the primary throttle, the air throttle is moved simultaneously therewith.

On opening of one or both of the throttle valves, the suction in the air chamber 90 is increased, and the valve 74 is opened to admit additional air and increase the quantity

- supplied to the engine. The opening of this valve is retarded to prevent fluttering of the valve and to restrict the admission of air to some extent whenever the throttles are open.
- 5 For this purpose a dashpot is provided comprising a cylinder 104 formed in the casting 30 and receiving fuel from the reservoir 32, and a piston 106 secured to the lower end of the air valve stem by any suitable means.
- 10 The resistance of this dashpot is controlled by means comprising an auxiliary cylinder 108 formed in casting 30 and closed at the lower end by a detachable plate 110, which also forms the bottom of the cylinder 104, a suitable gasket being provided between the plate and the casting 30 to prevent leakage. The cylinder 104 is connected with the cylinder 108 by a passage 112, bored in the casting 30 and communicating with the cylinder 104 at the bottom and cylinder 108 at the top, as shown in Fig. 1. The passage 112 connects with the cylinder 108, through a projecting surface 114 formed on the top of the cylinder 108, and a piston 116, which is slidably received in the cylinder 108, is normally held against the projection 114 by a spring 118 received between the piston and the plate 110. It will be clear, therefore, that until the piston 116 is moved to open the passage 112 the only escape of fuel from the cylinder 104 is by leakage around the piston 106 and resistance to opening of the air valve is high. When the pressure on the fuel in cylinder 104 is enough to disengage the piston 116 from surface 114 the resistance of the dashpot is much reduced because the fuel can escape from the cylinder 104 through passage 112 and orifices 120 formed in the piston 116 and through a restricted passage 122, leading from the cylinder 108 into another cylinder which forms part of the dashpot controlling movement of the auxiliary air valve in the manner hereinafter described.
- 45 As pointed out hereinbefore and fully shown and described in the above mentioned, earlier application, the valve 100 is opened by engine suction whenever the air throttle is opened. According to the present invention, the opening movements of this valve are retarded by means of a dashpot which is rendered relatively ineffective to accomplish this result when the auxiliary air valve is opened following an opening movement of the throttle when the engine is running at a relatively high speed. To accomplish this result, the shaft 102 on which the auxiliary air valve is mounted, has secured to one end thereof outside the main housing, an arm 130, which is pivotally connected by a pin and slot connection 132 to a link 134, the lower end of which is pivotally connected at 136 to a piston rod 138, yieldingly connected in a manner hereinafter described to a piston 140 which is slidably received in a cylinder 142, with which the passage 122, above referred to, connects. The piston 140 is secured in any desirable way to a tube 144, having a closed upper end through which the rod 138 extends. The tube 144 is also closed at the lower end by a screw cap 146 and slidably received within the tube is an enlarged head 148, formed on the lower end of the piston rod 138, while received between the said head and the upper end of the tube is a helical spring 150.
- 50 On any opening movement of the valve 100, the piston rod 138 is lifted and its movement is retarded relatively slightly by the action of the spring 150, which must be compressed as the valve is opened, and by the action of the dashpot piston 140, the movement of which is controlled by the rate of flow through the restricted passage 122, and also by the auxiliary piston 116, which must be moved out of engagement with the surface 114 before the piston 140 can move upwardly. The latter piston is moved by the main air valve as previously described.
- 55 When the main and auxiliary air valves are opened relatively slowly following such openings of the throttle as do not produce any great increase in suction on the valves the piston 116 is not disengaged from the surface 114 and fuel escapes from the dashpots only by leakage past the pistons, but when the valves 74 and 100 are opened very suddenly and by considerable force, as when the throttle is opened and the engine is already running rapidly, the effect of the dashpots controlling their motion is largely eliminated. As the main air valve is opened the piston 116 is moved out of engagement with the surface 114 so that the retarding effect of the piston on valve 74 is largely nullified and upward movement of the piston 140 retarded only by the limited rate of fuel flow through the passage 122, which may be of whatever size proves most desirable.
- 60 Moreover, when the valve is operated under the operating conditions described, the force effective to open such valve is great enough to collapse the spring 150 permitting the piston rod 138 to move relative to the piston 140, which will remain relatively stationary until the pressure of the spring becomes great enough to overcome the resistance offered to upward movement of piston 140, after which it will be slowly moved upwardly by the spring 150 until the parts assume the normal position shown in Fig. 1. After any opening movement of the valves 74 and 100 is completed the piston 116 will also be moved to its normal position so that following such movement the parts will assume their normal positions after a slight interval of time, and the resistance to any opening movement of the throttles will always be the same whatever positions the throttles may occupy at the time the opening movement begins.
- 65 It will be clear from the foregoing that

the action of the auxiliary dashpot is controlled by the main air valve through the medium of the piston 116 and the latter forms a valve mechanism operating to regulate the 5 resistance to opening movement of both air valves.

The secondary mixing chambers are identical in construction and each comprises a Venturi tube 160, which is held in position 10 adjacent the outlet of the primary mixture conduits in the manner fully disclosed in the above mentioned application. As this construction forms no part of the present invention, it will not be described in detail herein.

15 While the form of embodiment of the present invention as herein disclosed, constitutes a preferred form, it is to be understood that other forms might be adopted, all coming within the scope of the claims which 20 follow.

What is claimed is as follows:

1. A charge forming device for internal combustion engines comprising a mixing chamber, fuel and air inlets therefor, a throttle 25 controlling the flow of mixture therefrom, main and auxiliary air valves controlling the admission of air to the mixing chamber a plurality of, means for retarding the opening movements of these air valves and pressure 30 operated means for regulating the effect of all said retarding devices.

2. A charge forming device for internal combustion engines comprising a mixing chamber, fuel and air inlets therefor, a throttle 35 controlling the flow of mixture therefrom, main and auxiliary air valves controlling the admission of air to the mixing chamber, a plurality of dashpots for retarding the opening movements of said valves and a pressure 40 operated device for regulating the effectiveness of all of said dashpots.

3. A charge forming device for internal combustion engines comprising a mixing chamber, fuel and air inlets therefor, a throttle 45 controlling the flow of mixture therefrom, main and auxiliary air valves controlling the admission of air to the mixing chamber, a plurality of dashpots for retarding the opening movements of said valves and a single 50 means for regulating the effectiveness of all of said dashpots.

4. A charge forming device for internal combustion engines comprising a mixing chamber, fuel and air inlets therefor, a throttle 55 controlling the flow of mixture therefrom, an auxiliary air valve controlling the admission of air to the mixing chamber, a dashpot comprising a piston resiliently connected to the auxiliary air valve for retarding its opening movement, and valve means comprising 60 an auxiliary cylinder and piston valve slideable therein controlling the retarding effect of said dashpot.

5. A charge forming device for internal 65 combustion engines comprising a mixing

chamber, fuel and air inlets therefor, a throttle controlling the flow of mixture therefrom, main and auxiliary air valves controlling the admission of air to the mixing chamber, dashpots for retarding the movement of said valves, and a single valve means for controlling the outlet of one dashpot and the inlet of the other, whereby said valve regulates the retarding effect of both said dashpots.

70 6. A charge forming device for internal combustion engines comprising a mixing chamber, fuel and air inlets therefor, a throttle controlling the flow of mixture therefrom, main and auxiliary air valves controlling the admission of air to the mixing chamber, dashpots for retarding the opening movement of said valves, and valve means controlling the outlet of one dashpot and the inlet of another, said valve means comprising an auxiliary cylinder with which said inlet and outlet 75 communicate and a piston slideable therein.

80 7. A charge forming device for internal combustion engines comprising a plurality of primary mixture passages, means for supplying fuel and air thereto, a plurality of secondary mixing chambers to which said 85 passages deliver a primary mixture of fuel and air, a main air valve controlling the admission of air to said passages and to said secondary mixing chambers, an auxiliary air valve also controlling the admission of air to said secondary mixing chambers, dashpots for controlling the admission of air to said 90 valves and a common means for regulating the effect of both said dashpots.

95 In testimony whereof I hereto affix my signature.
